UNITED STATES PATENT OFFICE.

WILLIAM P. SHORTRIDGE, OF GRANFIELD, OKLAHOMA.

CUTTER.

1,133,753.

Specification of Letters Patent. Patented Mar. 30, 1915.

Application filed August 12, 1914. Serial No. 856,401.

To all whom it may concern:

Be it known that I, WILLIAM P. SHORTRIDGE, a citizen of the United States, residing at Granfield, in the county of Tillman 6 and State of Oklahoma, have invented certain new and useful Improvements in Cutters; and I do hereby declare the following to be a full, clear, and exact description of the invention, such as will enable others 10 skilled in the art to which it appertains to make and use the same.

The primary object of this invention is to provide a combination cutter of extremely simple and practical construction, which in 15 one form will be found useful in topping corn, pruning trees et cetera; and which in another form may be used as an ordinary knife for carving, slicing et cetera.

Another and more specific object of the 20 invention is to provide a cutter having a pair of pivoted handle bars between which operate a pair of pivoted blades.

The invention also aims to generally improve devices of this nature to render them 25 more useful, practically and commercially desirable.

With these and other objects in view as 30 will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a side elevation of my improved cutter, Fig. 2 is an end elevation 40 thereof, Fig. 3 is a plan view of the lower cutter blade, Fig. 4 is a similar view of the upper blade, Fig. 5 is a detail perspective view of the wire guard for the lower blade, Fig. 6 is a detail view, showing a lever 45 extension which may be connected to one of the handle bars of the cutter, Fig. 7 is a transverse sectional view taken on the plane of line 7—7 of Fig. 6, Fig. 8 is a side elevation, showing how parts of the cutter 50 may be omitted and the remaining parts used as an ordinary knife, Figs. 9, 10 and 11 are views illustrating different ways in which the lower blade may be connected to the lower handle bar.

Referring in detail to the drawings by numerals, 1 designates, as an entirety, the

lower handle bar of my improved cutter, said bar being formed preferably of a single piece of metal bent to provide curved side walls 2 and spaced parallel flanges or jaws 3, each 60 of which is provided with a longitudinal series of openings 4. The bottom wall of the handle bar 1 is extended beyond the side walls, as indicated by the numeral 5, and the edges of the extended portion are turned 65 upwardly and inwardly to provide sleeves 6 for a purpose to be hereinafter set forth.

An upper handle bar 7 preferably formed of a single piece of metal having ears or extensions 8 is pivotally connected at one end 70 to one end of the handle bar 1 by a screw bolt 9, said bolt extending through aligned openings formed in the ears 8 and side walls 2. A spring 10 is held in position between the handle bars 1 and 7 by the screw bolts 9 and 75 act to hold the bars normally in a spread position. The handle bar 7 is somewhat longer than the bar 1 and has secured to its inner side by means of a fastener 11, a spring plate 12, which is held against rotational movement by flanges 13 formed on the handle bar. The upper blade 14 having a cutting edge 15 provided, for a portion of its length with teeth 16, is pivotally connected 80 to the spring plate 12 by an ear 17 and pin 85 18. The ear is formed upon the upper edge of the blade adjacent the upper end thereof and extends through a longitudinal slot formed in the plate 12 and the pin 18 passes between the plate 12 and handle bar 7 and 90 through an opening formed in the ear. It will be noted upon reference to Fig. 1 that the plate 12 is bent away from the bar 7, as indicated by the numeral 19, to accommodate the pin. The blade 14 is formed with 95 a pair of longitudinal slots 20, through one of which a pivot bolt 21 passes, said bolt being extended through a pair of the openings 4 formed in the jaws 3. The lower blade 22 is longer than the upper blade 14 100 and is formed with a plurality of openings 23, through any one of which the pivot bolt 21 may be extended. The inner end of the blade 22 passes through a longitudinal slot 24 in the plate 12 and carries a roller 25 105 which rides against the inner side of the handle bar 7 when said bar is forced toward the handle bar 1.

It will be apparent that when the two handle bars are brought together, the blade 110 14 will sweep downwardly and rearwardly and the teeth 16 will cause a stalk or similar

object which is being cut to rotate in a clockwise direction, as viewed in Fig. 1, so that the point where the cutting action takes place is always as near the fulcrum or pivot bolt 21 as possible. The angle of the blade 14 relative to the blade 22 and the length of sweep of the blade 14 may be varied by running the pivot bolt 21 through the inner slot 20. The position of the blade 22 may also be adjusted by inserting the pivot bolt 21 through a different opening 23 and the position of the pivot bolt may also be changed, as will be apparent upon reference to Fig. 1.

The handle bar 1 carries a cutter guard, generally designated 26, which extends across the outer end of the blade 22 and prevents accidental injury thereby. This guard is of a somewhat U-shaped formation, having arms 27 which are received in the sleeve 5 and which are bent upwardly and outwardly adjacent their free ends, as indicated by the numeral 28. The outwardly projecting portion of the arms extend through openings 29 formed in the side walls 2 of the handle bar 1. When it is desired to shift the guard longitudinally to accommodate it to a different position of the blade 22, the extremities which extend through the openings 29 are first pressed inwardly, after which the guard may be shifted to any desired position.

The upper handle bar 7 carries a thumb guard 30, and the lower handle bar 1 carries a securing strap 31 which goes across the hand of the operator.

To provide for operating the cutter with both hands, I employ extension handles 32 and 33, the former being carried by the handle bar 7 and the latter being carried by the handle bar 1. The extension handle 32 has a cylindrical portion 34 formed with a spiral groove 35, and this cylindrical portion extends through a sleeve 36 forming a part of the socket member, generally designated 37. The socket member is connected to the top of handle bar 7 by the fastener 11 and is further connected thereto by a pair of ears 38 which are bent into engagement with the underside of said bar. As shown in Fig. 7, the sleeve 36 is provided with an interiorly arranged spring 38' which engages the periphery of the cylindrical portion 34 of the bar or extension 32. The bar 33, a portion only of which is shown in the drawing, is connected to the bottom wall of the handle bar 1 by a screw bolt 39 which extends through a longitudinal slot 40 formed in the bar. When the bar is used, the strap 31 is dispensed with.

In Fig. 8 I have shown how my cutter may be used as an ordinary knife by disconnecting the handle bar 7 and blade 14 from the remainder of the device. As shown in this figure, the handle bar 1 forms the handle of the knife, and the blade 22 is rig-

idly secured between the jaws 3 by a plurality of bolts 41.

In Fig. 9 I have shown the blade 22 inverted with respect to the position shown in Fig. 8 and when thus arranged the knife 76 is especially adapted for use as a paring instrument.

In Figs. 10, and 11 I have illustrated other positions in which the blade 22 may be secured.

From the foregoing description taken in connection with the accompanying drawings, it will be apparent that I have provided a very simple and practical cutter, which is adapted for various purposes and 80 which is capable of various combinations.

While I have shown and described the preferred embodiment of my invention, it will be understood that various changes in proportion, design and relative arrangement of parts may be made without departing from the scope and spirit of the invention as claimed.

Having thus described my invention, I claim:

1. In a cutter of the character described, a pair of handle bars pivotally connected to each other at one end, a pivot pin extending transversely through one of said handle bars, a blade connected to said pivot pin, a second blade connected to the other bar and formed with a longitudinal slot to receive said pivot pin.

2. In a cutter, a pair of handle bars pivotally connected to one another at one end, 100 one of the handle bars being formed with a pair of inwardly facing jaws, a blade extending between said jaws, a pivot pin extending through the jaws and blade, a second blade co-operating with said first mentioned blade, and means for pivotally connecting the second mentioned blade to the other handle bar, the second mentioned blade being formed with a longitudinal slot 105 through which the pivot pin passes.

3. In a cutter of the character described, a handle bar formed with a pair of opposed jaws, a blade extending between said jaws, means for securing the blade in position and a guard carried by the handle bar and extending across the outer end of the blade.

4. In a cutter of the character described, a handle bar formed with a pair of opposed jaws each provided with a series of openings, a blade extending between said jaws, a fastening member extending through certain of said openings and through the blade, and a longitudinally adjustable guard carried by the handle bar and extending across the outer end of the blade.

5. In a cutter of the character described, a handle bar formed with a pair of opposed jaws, each formed with a series of openings, a blade extending between said jaws having a series of openings, and a fasten-

ing member extending through registering openings formed in the jaws and blade.

6. In a cutter of the character described, a pair of handle bars pivotally connected to 5 one another to swing toward and away from each other, one of said bars being formed with a pair of opposed jaws, a blade extending between the jaws, a pivot pin extending through the jaws and blade, a second 10 blade pivotally connected at one end to the other handle bar and formed with a

longitudinal slot to receive said pivot pin, the inner end of the first mentioned blade being engaged by the inner face of the second mentioned arm when the arms are 15 forced together.

In testimony whereof I affix my signature in presence of two witnesses.

WILLIAM P. SHORTRIDGE.
